(57) **CLAIM**

The ornamental design for a cup holder ashtray, as shown and described.

DESCRIPTION

FIG. 1 is an isometric view of the cup holder ashtray, which embodies my design;

FIG. 2 is a perspective view of the cup holder ashtray showing my new design;

FIG. 3 is a bottom plan view thereof;

FIG. 4 is a side view thereof;

FIG. 5 is another side view thereof;

FIG. 6 is yet another side view thereof; and,

FIG. 7 is also yet another side view thereof.
